TYPE CASTING MACHINE

Shipley Myers and Albert Frederick Camp, London, England, assignors to The Kingsbury Engineering Company, Limited, London, England

Application November 9, 1937, Serial No. 173,555
In Great Britain March 2, 1937

13 Claims. (Cl. 199—95)

This invention relates to type casting machines of the kind capable of use for the production for stock of type pieces bearing each a single character or representation only, a matrix having as many "forms" as the maximum number of characters required to be produced being movable in two dimensions to bring individual forms one at a time into position for the casting of a predetermined number of type pieces successively therein, the casting being interrupted with the termination of the casting of each set of type pieces of like character (i. e. in one form) and said pieces being fed as they are cast into a "line" channel in which some at least (according to the number in a set) of said pieces remain at the termination of a corresponding casting operation, pieces which do not remain in said channel simply falling one by one by gravity as they reach the end of the channel. The usual line hook, which functions at the termination of each casting operation, does not move the more recently cast pieces far enough along the line channel to enable them to fall clear of the latter and, therefore, not only the placing of the sets of type characters in the corresponding or appropriate compartments of the usual type cases or compositor's trays, but also the removal of those pieces of each set which remain in the line channel at the termination of that casting operation which produced them has heretofore been effected manually.

As is well known in machines of this kind, the positioning of the matrix for the casting of individual type characters and the duration of each casting operation are determined by a common automatic control which operates according, for example, to perforations formed in a travelling paper roll by the operation of a keyboard.

The invention has for an object to avoid handling or manipulation of the type pieces.

To this end and in accordance with the invention, at the termination of the casting of each set of type characters a member under the common automatic control cooperates with the type character last formed and shifts all the characters in the line channel clear thereof.

Also according to the invention, delivery means under the common automatic control cause each set of type characters to be delivered into the corresponding or appropriate compartment of a compositor's tray.

For causing delivery of type characters into the corresponding or appropriate compartments of a compositor's tray, a chute extending downwardly from where the type characters leave the

line channel, or the lower part of such chute may be movable to bring the lower end of the chute into positions registering with the compartments, respectively, of a compositor's tray located therebelow.

Again, for causing delivery of type characters into corresponding or appropriate compartments of a compositor's tray a carriage for such tray may be movable under the common automatic control to bring individual compartments of the tray into register with falling type characters.

Yet again, for causing delivery of type characters into corresponding or appropriate compartments of a compositor's tray, a chute having a plurality of branches which correspond in number and in spacing at their lower ends with a single row of compartments in a compositor's tray may be movable under the common automatic control to register with several rows, one at a time, of the tray, the branches of the chute having shutters operating under the common automatic control to open one branch only at a time.

The invention is illustrated by the accompanying diagrammatic drawings of which Figure 1 is a plan view of the arrangement and operation according to one form of the invention of a member for shifting type pieces clear of the line channel (part being schematic and drawn to a reduced scale), Figures 2 and 3 being sectional views on the line 2—2 of Figure 1 and 3—3 of Figure 2, respectively;

Figure 4 is a schematic plan view drawn to a reduced scale of one form of delivery mechanism according to the invention for moving a carriage for a compositor's tray; Figure 5 shows in elevation the mechanism for moving the carriage of Figure 4 in one dimension, with Figure 6 as a corresponding plan view of one end of said mechanism; Figure 7 shows in elevation, and Figure 8 is a plan view of, the mechanism for moving said carriage in the other dimension; Figure 9 is a schematic plan view drawn to a reduced scale of means for automatically effecting movement of the carriage of Figure 4;

Figures 10 and 11 showing a detail in plan, and in sectional elevation on the line 11—11 of Figure 10, respectively;

Figures 12 and 13 are diagrams showing in side elevation further forms of delivery means according to the invention; whilst Figures 14 and 15 show to a reduced scale an arrangement for use with a compositor's tray having compartments of several sizes.

Referring first to Figures 1, 2 and 3, there is

indicated at 21 the usual table of an existing machine having upstanding ribs 22 defining therebetween the line channel, indicated at 23, the usual line hook being indicated at 24 in the position occupied thereby at the end of its operative stroke. According to the invention, that normally displaceable part of one rib 22 which is indicated by broken lines (Figure 1) is removed or moved out of position and there is journalled 10 in the table 21 a vertical spindle 25 having fast upon its upper end an arm 26 from which a pin 27 extends through a slot 28 in a block 29 to be received in a bore in an auxiliary line hook 30 pivotally mounted on the block at 31. The auxiliary line hook 30, see Figure 2, is comprised by upper and lower members disposed on opposite sides of the block 29 to engage with a type character at both the upper and lower parts of the latter; part of the arcuate guide 32 being cut 15 away at its under side to allow the lower member of said auxiliary line hook 30 to move between said arcuate guide 32 and the upper surface of the table 21. To the upper surface of the table 21 there are affixed the arcuate guide 32 and a plate 33 which together provide a curved extension 34 of the line channel 23. Reciprocating motion is imparted to the spindle 25 through the medium of a crank 35 and a pneumatic cylinder and piston, indicated at 36, the supply of air to 20 which is controlled by a valve 37 operated by an additional cam 38 on the usual cam disc 39 whereby motion is imparted to the normal line hook 24. It will be seen that when the arm 26 moves in a clockwise direction the pin 27 thereof will travel to one end of the slot 28 in the block 29, so rocking the auxiliary line hook 30 about its pivot 31 clear of the line channel extension 34 and will then carry with it the line hook and the block 29 to the end of the clockwise stroke. 25 Similarly, during anticlockwise movement the lever 26 will first move to carry the pin 27 thereof to the other end of the slot 28 in the block 29 so rocking the auxiliary line hook about its pivot 31 into position across the curved line channel extension 34 and will then move said block 27 and line hook 30 bodily therewith. To ensure such rocking of the lever 26 at the commencement of the clockwise and anticlockwise strokes, the block 29 (see Figures 2 and 3) has one margin shaped, as indicated at 40, to co-operate under the influence of a leaf spring 41 with undercut walls of a recess 42 in the arcuate guide 32; frictional co-operation of the block 29 with said walls ensuring that the block 29 shall not move until the pin 27 has reached one end or the other of the slot 28. At the outlet end of the curved line channel extension 34 the table 21 is formed with a delivery opening 43 through which type pieces, indicated at 44, fall upon leaving said extension 34, a delivery chute extending downwardly from said opening 43, as indicated at 45. The curved guide 32 is formed throughout that part of its length opposite to the plate 33 with a continuous projection 46 for engagement in the usual grooves in the type pieces 44 to resist any tendency of the latter to tilt during their passage along the curved line channel extension 34. The timing of the strokes 50

It will be understood that the mechanism just described is intended as a fitment to or modification of the auxiliary line hook 30 is such that the auxiliary line hook 30 commences each operative or type delivering stroke as or immediately after the normal line hook 24 completes its operative stroke.

tion of an existing machine which as a rule, if not invariably, will have insufficient space below the table 21 at the point where the type pieces 44 enter the curved line channel extension 34 to accommodate a delivery chute such as 45. In order that the auxiliary line hook 30, the arm 26, block 29 and the arcuate guides 32 and 33 shall not interfere with the normal delivery mechanism of the machine when the latter is used for composing, said parts may either together comprise a readily removable unit, or they may be so mounted individually upon the table 21 as to be readily removable therefrom. Also, if desired, means may be provided for closing the delivery opening 43 in the table 21. The outer curved 10 wall of the curved extension 34 of the line channel 23 may be adjustably and/or resiliently mounted so that the width of the curved channel extension 34 may be varied to suit type characters of different sizes. For this purpose the outer 15 wall of the curved extension 34 may itself be deformable, e. g. formed from thin sprung material.

It will also be seen that in some cases it may be possible, instead of providing an additional line hook such as 30, so to modify the mechanism 20 operating the normal line hook such as 24, that the operative stroke thereof may be increased so that it will remove all the type characters from the normal line channel.

In the delivery mechanism shown in Figures 4 30 to 11, a carriage for a compositor's tray is moved, each time the matrix of the machine is moved, to bring a corresponding compartment of a tray on the carriage into register with the place where type characters fall on leaving the line channel, 35 for instance, in the case of the arrangement described with reference to Figures 1, 2 and 3, into register with the lower end of the chute 45.

Referring first to Figure 4, two sets of guide rails 51 and 52, respectively, disposed at right-angles to one another carry two travelling frames 53 and 54 and serve together to support and to impart the desired motion to a carriage 55 for a compositor's tray (not shown). Movement in steps is imparted pneumatically to the two frames 35 53 and 54, the frame 53 having associated therewith two sets of cylinders and pistons 56 and the frame 54 having a single pair of cylinders and pistons 57. The frame 53 has a pair of racks 58 with which co-operate retractable plungers 59, and the frame 54 has a single rack 60 with which 40 co-operates a single plunger 61, said plungers 59 and 61 serving positively to locate the frames 53 and 54 in the various positions occupied thereby during delivery of type characters.

The cylinders 56 and 57 are mounted upon a base plate 62 which also carries the two sets of rails 51 and 52, and in the case of the frame 53 (see Figures 5 and 6) each cylinder 56 has a piston rod 63 protruding therefrom which is 45 connected with one arm 64 of a bell crank lever 64, 65 which latter arm is formed to engage the notches of the corresponding rack 58, said lever 64, 65 being fulcrumed at 66 upon a block 67 50 slidable on guide rails 68 supported at their ends 65 on the cylinders 56.

The pneumatic operation is such that the cylinders 56 at one side or the other only of the frame 53 function at a time to move said frame in one direction or the other through a distance 70 corresponding with the distance between adjacent rows of compartments in a compositor's tray in position on the carriage 55, the stroke of each slide block 67 being limited in one direction by the mounting of the guide rods 68 on the corre- 75

sponding cylinder 56 and in the other direction by a fixed housing 69 for the plunger 59 carried on the guide rods 68. The slideable block 61 on which the bell crank lever 64, 65 is mounted may be spring or frictionally loaded to ensure proper or full engagement of said lever 64, 65 with a notch of the rack 58 before the block 61 is shifted.

The plunger 59 extends downwardly from its housing 69 and when in the locking position is spaced at its lower end from the base plate 62 by a distance only slightly greater than the depth or length of the teeth on the rack 58, this downwardly extending part of the plunger 59 being in lost motion connection with corresponding ends 15 of two levers 70, 71, 70, 71 the arms 70 of which extend between flanges 72 on the plunger 59. The levers 70, 71 are fulcrumed about a common pivot 73 and the arms 71 thereof extend over pneumatically operated plungers 74 (see Figure 20 6), the raising of either of which results in downward movement of the arm 70 of the corresponding lever 70, 71 into co-operation with the lower flange 72 on the plunger 59 and therefore in retraction of the latter from the rack 58. Each 25 lever 70, 71 has a pin 75 extending therefrom over an axially slideable valve member 76 the head 77 of which normally co-operates with a seating 78 to shut off from a supply of compressed air (see Figure 9) connected with a port 79 from the cylinder 56 at the corresponding side of the plunger 59 which cylinder has an inlet 80 connected with the outlet 81 of the valve. Each 30 plunger 74 (as indicated by dotted lines in Figure 5) is movable in a cylinder 82 having an inlet 83 connected with the supply of air under pressure.

Admission of air to a cylinder 82 raises the corresponding plunger 74 and depresses the arm 70 of the corresponding lever 70, 71, the pin 75 of which co-operates with the corresponding valve member 76 and depresses the latter to place the corresponding cylinder 56 into communication via the inlet 79 with the above-mentioned air supply. The downwardly moving arm 45 70 also co-operates with the lower flange 72 on the plunger 59 and retracts the latter from the rack 58. As a result the corresponding bell crank lever 64 is rocked about its fulcrum 66 to bring the arm 65 thereof into co-operation with a notch of the rack 58 and then the slide block 67 moves from the position shown into contact with the plunger housing 69 carrying with it the rack 58 and frame 53 through a corresponding distance which is equal to the width of one compartment of the tray (not shown). In order to ensure that movement as described of one lever 50 70, 71 shall retract the plunger 59 and yet open one only of the valves 76 the distance between the upper end of each valve member 76 when closed and the pin 75 of the corresponding lever 70, 71 when in its normal position as shown, is greater than the distance between the lower end of the plunger 59 and the base plate 62.

The mechanism for imparting movement in 55 steps to the frame 53 is as above indicated the same as that for moving the frame 53 except that only two cylinders 57 and a single rack 68 and plunger 61 are employed. In this case (see Figures 7 and 8), the two cylinders 57 are mounted 60 on the base plate 62 with their piston rods 84 connected with a bell crank lever 85 fulcrumed at 86 upon a block 87 slideable, if desired, against frictional or spring resistance, on guide rods 88 between the mountings of said rods 88 on the cylinders 57 and a fixed housing 69 carried by the

rods 88 for the plunger 61. Also the mechanism associated with the plunger 61 is equivalent to but not precisely the same as the mechanism for operating the plunger 59, two levers 90 extending in opposite directions instead of alongside 5 one another as do the two levers 70, 71. The levers 90 are forked at their ends (see Figure 8) and each has a laterally extending pin 91 which instead of co-operating directly with a valve member co-operates with one end of a further 10 lever 92 which acts upon a valve member 93 at its other end. This valve member controls the connection of the corresponding cylinder 57 with the source of compressed air in the same way as the valve member 76 controls the connection of 15 the cylinders 56 with said source. The pneumatic plungers for actuating the levers 90 are indicated at 94, the connection of the air supply thereto at 95, and the inlet and outlet for air past the valve member 93 at 96 and 97, respectively, and the inlet for air to the cylinders 57 at 98.

The operation of the mechanism described is controlled by the normal or existing automatic control of the machine in which a paper strip, indicated at 99 in Figure 9 of the drawings, is 25 fed continuously over the open ends of a series of air pipes 100 to determine into which of these compressed air can enter from a common supply chest 101. As is well known there is as a rule a considerable number of such pipes 100 but only 30 five of these are utilized for the purposes of the invention, these five alone being shown in the drawing. Each of these five pipes is tapped or branched, as indicated at 102, so that air entering it actuates or controls part of the mechanism according to the invention as well as part of the machine normally actuated or controlled thereby.

It will be remembered that the supply of air to each of the cylinders 56 and 57 is controlled by a corresponding valve 76 or 93, these valves 40 being in turn operated by pneumatic plungers 74 or 94. Each plunger 74 or 94 receives air under pressure by which it is operated to open the corresponding valve from the same source as the cylinders 56 and 57 under the control of the 45 corresponding one of a number of valves in a chest 103, the two pneumatic plungers 74, actuation of which results in movement of the carriage 53 in the one direction, being controlled by the valve 104, and the other two plungers 74 50 being controlled by the valve 105, whilst of the two plungers 94, one is controlled by a valve 106 and the other by a valve 107 in said chest 103. A further valve 108 in the chest 103 serves to connect the inlet sides of the valves 104, 105, 106 55 and 107 with the air supply, indicated at 109, and all of the valves 104, 105, 106 and 107 are operated by air reaching the chest 103 according to apertures formed in the paper strip 99 passing over the open ends of the pipes 100.

The valve chest 103 is shown more clearly in Figures 10 and 11. Each valve 104, 105, 106, 107 and 108 is in the form of a plunger and as shown in Figure 11 in the case of the valve 104 comprises a head 104A having a stem 104B with which co-65 operates one end of a corresponding rocking lever 104C bearing at its other end upon a pneumatic plunger 104D raising of which latter by air via the corresponding pipe 100 and branch 102 opens the valve. Air outlet pipes from the valves 104, 70 105, 106 and 107 are indicated in Figure 10 at 104X, 105X, 106X, and 107X and the inlet sides of these valves are connected with one another by a bore 110 in the chest 103 and via a pipe 11 with the outlet side 108X of the valve 108, the 75

inlet 108Y of which is connected with the air supply 109.

It will be seen that when the carriage 55 is stationary, for example, during the casting operation, air from the supply 109 is shut off from the cylinders 56 and 57 by the valves 76 and 93, respectively, and from the inlets of the valves 104, 105, 106 and 107 by the valve 108. At the termination of a casting operation air from the chest 101 is allowed by an aperture in the paper strip 99 to open the valve 108 thus placing the valves 104, 105, 106 and 107 into communication with the air supply 109, then, according as a compositor's tray on the carriage 55 requires to be moved in one or both dimensions to bring into position for the reception of type the compartment of the tray appropriate to the characters next to be cast, the appropriate valve or valves of the group 104, 105, 106 and 107 is or are opened to effect the necessary movement steps of one or both of the frames 53 and 54 and thus of the carriage 55.

Each of the pipes 100 which is branched for the purposes of the present invention will in general be one the passage of air through which alone will not bring about any operative function of the machine as apart from the present invention, e. g. in moving the matrix, and further that pipe 100 which is tapped for the control of the valve 108 will be one the passage of air through which renders the machine incapable of casting. Not until air ceases to pass through this pipe will the next positioning of the matrix to determine which type character shall next be cast take place. Thus, it will be noted that the tapping of the pipes 100 apart from that leading to the valve 108 will in no way affect matrix positioning or other operations of the machine because opening of any one or more of the valves 104, 105, 106 and 107 when the valve 108 is closed is ineffective.

All the members which are shifted pneumatically according to the invention are returned to their normal positions by springs which for the sake of clearness are not shown in the drawings.

Means, not shown, may be provided for enabling any or all of the valves 104, 105, 106, 107 and 108 to be operated at will manually.

The mechanism described with reference to Figures 4 to 11 is for imparting movement to a compositor's tray beneath a fixed delivery outlet for type as indicated in the opening paragraphs of the specification. However, a compositor's tray may in some cases remain stationary and an outlet for type may be moved instead, by mechanism similar to, but of lighter construction than, that described with reference to said figures. For example, as shown in Figure 12, a chute such as 45 of Figure 1 may have its lower end formed as indicated at 121 and terminating above a funnel-shaped type delivery member 122, the outlet 123 of which corresponds in cross-sectional area with individual compartments of a compositor's tray indicated at 124, this funnel being carried by rollers 125 running in rails 126 extending in one dimension and on a carriage 127 mounted for movement on rails 128 extending in the other dimension. It will be noted that in such an arrangement the intake end of the delivery member 122 will be of the same shape and at least of the same size as the tray 124.

Again, as above indicated, a delivery chute such as 45 Figure 1 may feed the type to a branched delivery chute at 129 (Figure 13) which

latter as a whole is pivoted about an axis 130. The outlet orifices 131 of the branched chute 129 are disposed in a straight line and correspond in number with the number of compartments in a row of a compositor's tray, indicated at 132, each branch being controlled by a pivoted shutter 133 so that type entering the chute 129 can issue therefrom via one only at a time of the outlet orifices 131 to determine into which of the compartments of a row type characters shall be fed for any casting operation. The automatic control means in this case serves to bring about the operation of the shutter 133 and also to bring about movement of the chute 129 as a whole about its pivot 130 to bring the outlets 131 into register with the different rows of compartments of the tray 132. It will be seen from a consideration of Figure 13 that the shutters 133 are so arranged that those in the lowermost row may be operated simultaneously as by a control rod 134 and that the intermediate pair of shutters 133 also may be operated by a single control rod 135, the single shutter 133 at the top having a control rod 136.

In order to provide clearance for the usual flange or upstanding wall at one side of a compositor's tray it is necessary that a chute from which type characters fall into the tray should terminate some distance thereabove. In order, so to speak, to fill in the gap between the top of the tray and the lower end of the chute there is provided a device resembling a bottomless tray which is placed in position above the tray to constitute upward extensions of all the walls thereof, thus effectively preventing any jerking of the characters from one tray compartment to another. It will be clear how the correct delivery of different type characters into the corresponding or appropriate compartments of a compositor's tray, having compartments all of the same size, is ensured. This device just mentioned will always have what may be termed bottomless compartments all of the same size and, in a case where a tray to be filled has compartments of different sizes some of the walls of the device will be extended downwardly to divide the larger compartments of the tray properly temporarily into separate compartments, thus effectively preventing any possible jerking of piled up characters from one compartment into another, and also ensuring even or uniform filling of the larger compartments. This is illustrated by Figures 14 and 15 of the drawings, of which Figure 14 shows a tray in plan and Figure 15 in sectional view on the line 15—15 of Figure 14 with the device just mentioned in position thereon. As will be seen the tray has large and small compartments 151, 152, and compartments 153 of intermediate size. In Figure 15 the usual upstanding flange at one side of the tray is indicated at 154 and the bottomless tray device at 155. It will be seen that this device 155 extends over the whole of the compositor's tray and is flush at its upper surface. Some of the partitions or compartment walls 156 constitute simply upward extensions of the compartment walls 157 of the tray, whilst other compartment walls 158 of the device extend downwardly into the large compartments 151 of the tray to divide them temporarily into compartments of smaller size.

Although in all the cases described use is made of the pneumatic type of automatic control common in machines of the kind to which the invention relates, it will be apparent that

other forms of control may be employed. For example, the various operations or movements of the mechanism according to the invention may be brought about automatically as a result of electric circuits being broken or completed instead of by the open ends of air pipes being covered or uncovered by a travelling paper strip which latter in such case may carry contact pieces or strips for co-operation with fixed contacts instead of being formed with apertures.

What we claim to be new is:

1. The combination with a type casting machine of the kind referred to for making type castings presenting a plurality of different characters, a single casting presenting a single character, which machine includes mechanical control means actuatable to selectively determine the character presented by a casting discharged from said machine, of means for delivering castings discharged from said machine in to a compositor's tray comprising a plurality of compartments and means actuatable in response to actuation of said control means adapted to determine the compartment of said tray into which said castings are delivered according to the character presented by said castings as selectively determined by said control means.

2. The combination with a type casting machine of the kind referred to for making type castings presenting a plurality of different characters, a single casting presenting a single character, which machine includes a discharge aperture and mechanical control means actuatable to selectively determine the character presented by a casting discharged from said discharge aperture of said machine, of means actuatable in response to actuation of said control means adapted to shift relatively to said discharge aperture a compositor's tray having a plurality of compartments therein so that the castings discharged from said discharge aperture are delivered into different compartments of said tray depending upon the character presented by said castings as selectively determined by said control means.

3. In or for a type casting machine of the kind referred to, delivery means which operate under the common automatic control of the machine to cause each set of type characters to be delivered into the corresponding or appropriate compartment of a compositor's tray and in which a chute extending downwardly from where the type characters leave the line channel, or the lower part of such chute, is movable to bring the lower end of the chute into position registering with compartments, respectively, of a compositor's tray located therebelow.

4. In a type casting machine of the kind referred to, mechanism which operates under the common automatic control of the machine at the termination of each casting operation and which comprises an auxiliary line hook that is adapted to cooperate with type pieces already shifted along the line channel by the normal line hook of the machine to shift them clear of the channel, said auxiliary line hook being mounted for limited pivotal movement on a block slidable to and fro in the direction of the line channel, and an arm movable to and fro about a center and adapted to cooperate with the auxiliary line hook during each to and fro movement thereof to cause said hook to move pivotally into or out of the path of type characters in

the line channel and then bodily as one with said block in the direction of said channel.

5. Mechanism as claimed in claim 4, wherein the delivery end portion of the line channel is of circular curvature substantially about the center about which the arm moves to and fro to impart movement to the auxiliary line hook, the inner wall of the curved portion of the line channel being extended beyond the end of the latter and formed with an undercut longitudinal groove to constitute a support guide for the block which cooperates frictionally therewith, substantially as described.

6. Mechanism, as claimed in claim 4, wherein the auxiliary line hook has upper and lower members for engaging with the upper and lower ends of a type character, the inner wall of the line channel being cut away or slotted at its lower part to give passage to the lower member of the auxiliary line hook.

7. In a type casting machine of the kind referred to including means for effecting relative movement between a compositor's tray and a chute adapted to deliver castings into said tray, said means comprising two frames travelling on two guides mounted on a suitable foundation and disposed respectively at right angles to one another, one frame being movable along one of said guides to shift said tray or the lower end of said chute in one dimension and the other frame being movable along the other of said guides to shift the tray or lower end of the chute in the other dimension, each frame having a series of notches, and a retractable stop being carried by said foundation adapted for cooperation with said notches to maintain each of the frames in predetermined positions.

8. A machine according to claim 7 including means for imparting movement in steps to each frame, said means comprising a movable member mounted on said foundation, means for moving said member, and a lever which has one arm thereof pivotally connected to said member and which is pivotally mounted intermediate its length upon a slide block mounted for movement in the same direction as the corresponding frame, said arrangement of member, lever and block being such that movement of the movable member initially rocks the lever to bring the other arm of said lever into cooperation with a notch of the corresponding frame and subsequently shifts the block, lever and frame as one.

9. A machine according to claim 7 including means for imparting movement in steps to each frame, said means comprising a pneumatic cylinder and piston that is pivotally connected to one arm of a lever pivoted intermediate of its length upon a slide block mounted for movement in the same direction as the corresponding frame, said arrangement of piston, lever and block being such that movement of the piston initially rocks the lever to bring the other arm of said lever into cooperation with a notch of the corresponding frame and subsequently shifts the block, lever and frame as one, and a similar arrangement of cylinder, piston, lever and block for moving said frame in the opposite direction, each cylinder receiving air through a normally closed valve adapted to be opened in response to movement of each of two independent actuating means for retracting said stop, the operation of one of said retracting means resulting in the opening of the valve controlling one of said cylinders and the operation of the other of said retracting means resulting in

the opening of the valve controlling the other of said cylinders.

10. In a type casting machine of the kind referred to including means for effecting relative movement between a compositor's tray and a chute adapted to deliver castings into said tray, said means comprising a frame movable along a guide mounted on a suitable foundation to shift said tray or the lower end of the chute, a first pneumatic cylinder and piston mounted on said foundation and operatively connected to said frame to move said frame in one direction, a second pneumatic cylinder and piston mounted on said foundation and operatively connected to said frame to move said frame in the opposite direction, a retractable stop carried by said foundation adapted to cooperate with notches in said frame to maintain said frame in predetermined positions, first and second valves for controlling the air supply to said cylinders, first and second rocking levers which are adapted to contact an operating member of said first and second valves respectively to open said valves and each of which has a lost motion connection with said stop; the arrangement being such that upon rocking one of said levers said stop is retracted and one only of said valves is opened, the lost motion connection of the levers with the stop ensuring that the other lever is not shifted far enough by the stop during retraction thereof to open the other valve.
11. A machine according to claim 10 wherein a supply of air under pressure is normally open to said valves controlling passage of air to the pneumatic cylinders and also to a further valve controlling the passage of air to a valve chest and which comprises a first and second pneumatic plunger adapted to impart rocking motion to said levers to retract said stop and open said valves

controlling the passage of air to said cylinders, and air lines controlled by valves in said valve chest communicating with said pneumatic plungers; the arrangement being such that to operate either of said plungers the valve controlling the admission of air to the valve chest must be open and the valve in the valve chest controlling the air line to said plunger must be open.

12. The combination with a type casting machine of the kind referred to for making type 10 castings presenting a plurality of different characters, each casting presenting a single character, which machine includes pneumatic control means comprising a plurality of air lines controllable to selectively determine the character presented 15 by a casting discharged from said machine, of means for effecting relative movement between a compositor's tray and a chute adapted to deliver castings discharged from said machine into said tray, said means comprising air pipes connected 20 to said air lines and communicating with mechanism operable to effect said relative movement, so that operation of said pneumatic control means to determine the character of a casting discharged from said machine also effects a 25 relative movement between said compositor's tray and chute according to the character presented by the castings selectively determined by operation of said pneumatic control means.

13. Apparatus according to claim 1, wherein a 30 bottomless tray is interposed between said compositor's tray and said machine, said tray having compartments at least some of which register with compartments of said compositor's tray and being adapted to promote the retention of said 35 castings in the compartments of said compositor's tray.

SHIPLEY MYERS.
ALBERT FREDERICK CAMP.

CERTIFICATE OF CORRECTION.

Patent No. 2,156,638.

May 2, 1939.

SHIPLEY MYERS, ET AL.

It is hereby certified that error appears in the printed specification of the above numbered patent requiring correction as follows: Page 2, first column, lines 69 and 70, strike out the words and syllable "It will be understood that the mechanism just described is intended as a fitment to or modifica—" and insert the same before line 1, second column, same page; and that the said Letters Patent should be read with this correction therein that the same may conform to the record of the case in the Patent Office.

Signed and sealed this 27th day of June, A. D. 1939.

Henry Van Arsdale
